TRAVELING CONTACTING DEVICE

Burtis W. Benbow, Benbow, Calif.

Application January 30, 1945, Serial No. 575,300

3 Claims. (Cl. 191—59)

1

This invention relates generally to traveling contacting devices suitable for use with trolley wires.

In Benbow 2,255,874 there is disclosed a traveling contacting device making use of endless series of conductor elements which are adapted to make continuous electrical connection with a trolley wire. In practice the conductor elements can be carried by a trolley box or like body, which also carries one or more bus bars disposed in spaced parallel relationship with the trolley wire. The series of conductor elements is arranged to pass between the bus bars and the trolley wire, and is also tracked upon a pair of wheels. A traveling connecting device of this type is particularly adapted for use with a trolley wire having an insulating sheath to protect the same against accidental contact, with one side of the sheath having spaced recesses extending through the same whereby the conductor elements may enter the recesses for electrical contact with the wire.

It is an object of the present invention to provide an improved traveling contacting device of the above character having improved means for tracking the series of conductor elements within the trolley box.

A further object of the invention is to provide means serving to prevent excessive lateral sagging or misalignment of the conductor elements when the device is operated in a position other than vertical, as for example in a horizontal position.

A further object of the invention is to improve upon the construction of the conductor elements and the means employed for connecting the same together.

Additional objects of the invention will appear from the following description in which the preferred embodiment has been set forth in detail in conjunction with the accompanying drawing.

Referring to the drawing—

Figure 1 is a side elevational view, partly in cross-section, showing a traveling contacting device incorporating the present invention.

Figure 2 is a cross-sectional view taken along the line 2—2 of Figure 1.

Figure 3 is a cross-sectional view taken along the line 3—3 of Figure 1.

The apparatus illustrated in the drawing consists of a traveling contacting device 10 which is adapted to operate in conjunction with a trolley wire assembly 11. The trolley wire assembly in this instance consists of a trolley wire 12 surrounded by a protective sheath 13 of insulating material, such as natural or synthetic rubber.

2

The back side (upper side as illustrated) of this sheath is retained by the substantially T-shaped metal backing or mounting strip 14. The lower side of the sheath, or what is normally the lower side when the contacting device 10 is operated in a vertical position, is provided with a series of recesses 16, separated by the teeth-like bars 17 of insulating material formed integral with the remainder of the sheath. Recesses 16 permit electrical contact with the trolley wire 12 as will be presently explained. A suitable length of the assembly 11 is supported at intervals by the brackets 18.

The trolley contacting device 10 consists of a body 20 which can be formed of suitable molded insulating material, and split to form the two halves or sections 20a, 20b. Carried by this body there is an endless series of articulated conductor elements 21. Each of these elements consists of an outer tooth-like portion 21a, the end face of which is notched or grooved as indicated at 21b to facilitate seating upon the wire 12. The base portion 21c of each element is provided with a slot or recess 22.

The means for connecting adjacent elements 21 preferably consists of links 23 which have their ends pivotally connected to elements 21 by the pivot pins 24. The end portions of links 23 are accommodated within the slots 22.

The body 20 also carries bus bar means for making continuous electrical contact with the elements 21. In this instance such means includes a pair of aligned bus bars 26 made of suitable material such as hard copper or bronze, and having pivotal connections 27 to the L levers 28. L levers 28 are carried by the common pivot pin 29, and are urged by compression spring 31 in a direction to urge the bus bars 26 upwardly. Stranded conductors 33 are also shown for electrically connecting bus bars 26 to the terminal plate 34. The conductor elements 21 are adapted to pass between the bus bars 26 and the trolley wire 12 whereby the bus bars are continuously electrically connected with the trolley wire through the elements 21. It will be noted that the base portions 21c of elements 21 have flat faces 21d, for good sliding contact with the bus bars 26. The elements 21 are also tracked upon a pair of spaced sprocket wheels 36. These wheels are suitably journaled to the body 20 as by providing them with roller bearings 37 to the shafts 38. The teeth 39 on these sprocket wheels are shaped and dimensioned so that they are accommodated within the slots or recesses 21, intermediate the

elements 21.

adjacent links 23. Thus the sprocket wheels not only serve the purpose of tracking the elements 21, but in addition the teeth of the sprockets retain the elements 21 against excessive lateral misalignment. The end portions 26a of the bus bars 26 are preferably forked or bifurcated as illustrated whereby each slot thus provided serves to accommodate the peripheral portion of the adjacent sprocket. In addition each end portion 26a is formed to provide the curved surface 26b to facilitate transfer of an element 21 from a sprocket to the adjacent bar 26 or from a bar 26 to an adjacent sprocket wheel.

In order to retain the contacting device 10 in operating position, two pairs of flanged wheels 41 are provided, and are adapted to operate along the flat trackways 42 provided by the backing strip 14. Wheels 41 are journaled to the upper ends of bars 43, which in turn are secured to the sides of the body. Members 41 which are shown attached to the ends of one of the shafts 38, represent means whereby the contacting device 10 can be moved to different operating positions in accordance for example to the movements of a crane carriage.

Operation of the device described above is as follows: Assuming that the contacting device 10 is operatively positioned with respect to the trolley assembly 11 as shown in Figure 1, a plurality of the elements 21 are at all times in contact with the wire 12, and with the bus bars 26. As the contacting device is moved the sprocket wheels 36 rotate, and assuming that the direction is toward the left as viewed in Figure 1, the tooth-like portions 21 enter the recesses 16 at the advancing end of the device, and leave at the trailing end. While the elements 21 are carried by the sprocket wheels 36 the sprocket teeth 39 are well within each element, and therefore the elements are retained against excessive lateral displacement out of line with the recesses 16. This is advantageous because it insures proper entry of the tooth-shaped portions 21a into the recesses 16 without possible interference with the insulating portions 17, even though the contacting device may occasionally or continuously be operated in an inclined or horizontal position, instead of in a vertical position as shown in Figure 1. In addition to the advantages mentioned the linkage connection between elements 21 is extremely simple, and the links themselves aid in proper retention of elements 21 upon the sprocket wheels.

I claim:

1. In a traveling contactor device for a trolley wire, a body, at least two aligned bus bars mounted upon the body for movement parallel to and in spaced relation to the wire, an endless series of articulated conductor elements mounted for movement between the bus bars and the wire to provide a conducting path therebetween, and wheels located adjacent the ends of the bus bars for tracking said elements, the end portions of the bus bars adjacent said wheels being bifurcated to accommodate the peripheral portions of the wheels.
2. In a traveling contactor device for a trolley wire, a body, bus bar means carried by the body and adapted to move parallel to and in spaced relationship to the wire, a series of articulated conductor elements mounted for movement between the bus bar means and the wire to provide a conducting path therebetween, each conductor element having a tooth-like portion with an end face for contacting the wire and also a longitudinally slotted base portion with an end face for sliding contact with the bus bar means and which is interrupted by said slot, and a sprocket wheel journaled to the body and over which the articulated conductor elements are tracked, the slots in said base portions of said elements serving to accommodate the teeth of the sprockets.
3. In a traveling contactor device for a trolley wire, a body, bus bar means mounted on the body for movement parallel to and in spaced relation to the wire, an endless series of articulated conductor elements mounted for movement between the bus bars and the wire to provide a conducting path therebetween, and sprocket wheels located adjacent the ends of the bus bar means for tracking said elements, the end portions of the bus bar means adjacent said wheels being bifurcated to accommodate the peripheral portions of the wheels, the conductor elements having recesses to accommodate the teeth of the sprocket wheels.
